UNITED STATES PATENT OFFICE.

HORACE F. BANAN, OF PITTSBURGH, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed June 9, 1920. Serial No. 387,579.

To all whom it may concern:

Be it known that I, HORACE F. BANAN, a citizen of the United States, and a resident of Pittsburgh, in the county of Allegheny and State of Pennsylvania, have invented a new and useful Improvement in Thermal Relays, of which the following is a specification.

My invention relates to thermal relays and particularly to bimetallic relays.

One object of my invention is to provide a relay having a thermal-responsive device that inherently shall have such heating characteristics as to ensure effective operation when connected in circuit with a device to be protected, without the use of auxiliary heating devices.

Another object of my invention is to provide a bimetallic member that inherently shall have high electrical resistance.

Another object of my invention is to provide a relay of the cartridge type that shall have means whereby the thermal elements and contact members thereof may be mounted as a unit on one ferrule of the cartridge.

A further object of my invention is to provide a relay, of the above indicated character, that shall be simple and inexpensive to construct and effective in its operation.

Heretofore, when thermal relays were used for the protection of electrical apparatus, it was found desirable, especially when the device to be protected consumed a relatively small value of current, to provide a heating element for the thermal-responsive member. This was found necessary by reason of the fact that insufficient heating was obtained when the thermal-responsive device was made of such mechanical structure as to secure effective operation.

In view of the above, I provide a bimetallic member of the required mechanical strength to obtain effective operation and I slit the same alternately from opposite ends thereof to constitute an electrical conductor having relatively high resistance. It will be seen that, with this arrangement, sufficient heat may be generated in a relatively large bimetallic member, by a relatively small current traversing the same, to cause effective operation thereof. I further mount the bimetallic element and the contact members, as a unit, on one ferrule of a

device of the cartridge type, in order to ensure, at all times, effective alinement between the contact members and consequent accuracy of operation.

Figure 1 of the accompanying drawings is a view of the bimetallic element embodying my invention.

Fig. 2 is a view of the element shown in Fig. 1 having bracing members at the ends thereof.

Fig. 3 is a view, partially in elevation and partially in section, of a thermal relay embodying my invention, and

Fig. 4 is a diagram illustrating the use of my invention for the protection of an electrical translating device.

A motor 1 or other electrical translating device, to be protected, is provided with current from a circuit 2 through an interrupter 3. The interrupter 3 is provided with a low-voltage holding coil 4 and a spring 5 for actuating the same when the coil 4 is de-energized. The circuit of the coil 4 is controlled by a thermal relay 6 which is connected in circuit with the motor 1.

The thermal relay 6, as shown in Fig. 3, comprises a cylindrical casing 7, two end ferrules 8 and 9 and a unitary thermal-responsive device 10. The unitary thermal-responsive device 10 comprises an insulating block 11 to which is secured a bimetallic member 12 and an arm 13 upon the outer end of which is mounted a contact member 14. A contact member 15 is mounted on the bimetallic member 12 but is insulated therefrom and is adapted to engage the contact member 14. The block 11 is secured to the ferrule 8 by rivets 16.

The bimetallic member 12 comprises two strips of metal 17 and 18 having different temperature coefficients and effectively secured together in face-to-face relation. Slits 19, 20 and 21 are cut in the member 12 from the respective ends thereof in such manner as to greatly increase the resistance to the flow of current therethrough. That is, with the bimetallic member slit as shown in Figs. 1 and 2, the resistance to the flow of current from the point 22 to the point 23 is substantially sixteen times as great as the resistance to the flow of current from one end to the other of the original strip. The point 22 of the strip is electrically connected

to the ferrule 8 by soldering the same thereto, and the point 23 is connected, through a conductor 24, to the ferrule 9. That is, the conductor 24 is disposed around one end 5 of the casing 7 in intimate engagement with the ferrule 9 to thus effectively place the bimetallic member 12 in circuit with the motor 1. The contact member 15 is electrically connected, through a flexible conductor 10 31, to the conductor 24 to preclude the control current traversing the strip 12. The ferrules 8 and 9 are adapted to be received by ordinary cartridge-fuse clips. However, the spacing of the clips is such as to pre- 15clude the use of a device of this type in place of a fuse of the same rating.

Two insulating members 25 and 26 are clamped to the outer end of the bimetallic element 12 for the purpose of so strengthening 20 the same as to preclude uneven expansion of the various parts of the element and also for the purpose of insulating the contact member 15 from the strip 12. The contact member 14 is connected, through the 25 supporting member 13 and a conductor 27, to a terminal post 28 which, in turn, is connected, through the coil 4, to conductor 29 of the circuit 2. It will be understood that the relay 6 is placed in series with conductor 30 30 of the circuit 2 in order that the coil 4 may be connected across the circuit.

Since the bimetallic element 12 is disposed in the casing 7 and, since the resistance to the flow of current through the element 12 35 is relatively high, it will readily be seen that the device may be adjusted to cause disengagement of the contact members 14 and 15 when a predetermined value of current has traversed the motor 1 for a predetermined 40 interval of time.

The heating characteristics of the device 45 6 may be such as to conform exactly to that of the motor 1 or they may be such that the time interval is sufficient to secure adequate protection to the motor 1.

With my device, adequate protection will be obtained, irrespective of the current traversing the motor 1. That is, if the motor 1 consumes only a fraction of an ampere, sufficient heating will obtain in the element 12 50 to cause the same to operate effectively to de-energize the coil 4 which permits the spring 5 to open the interrupter and thus disconnect the motor 1 from the circuit. The coil 55 4, being a low-voltage coil, will, of course, also permit the interrupter 3 to open when the voltage across the circuit 2 falls below a predetermined value.

Since the unit 10, comprising the bimetallic element 12 and the contact members 14 60 and 15, is mounted on one ferrule of the device, it will be understood that the necessity for accurate alinement of the ferrules 8 and 9 is obviated and thus a more accurate de- 65 vice is obtained with less expense.

My invention is not limited to the specific structure illustrated as it may be variously modified without departing from the spirit and scope of the same, as set forth in the appended claims.

I claim as my invention:

1. An article of manufacture comprising a bimetallic strip having slits therein extending alternately from opposite ends.

2. An article of manufacture comprising a bimetallic strip having such slits therein, extending from the respective ends thereof, that the resistance of the strip is relatively large.

3. An article of manufacture comprising two strips of material of different coefficients of expansion positively secured together in face-to-face relation and having slits therein extending from opposite ends thereof.

4. An article of manufacture comprising two strips of material of different coefficients of expansion positively secured together in face-to-face relation and having slits therein extending from the ends thereof.

5. A thermal relay comprising a bimetallic strip having a plurality of slits therein extending from one end to increase the electrical resistance thereof.

6. A thermal relay comprising a bimetallic strip having slits of such lengths, extending alternately from the respective ends thereof, as to increase the electrical resistance of the strip, means joining the portions so formed to cause them to move together when heated, and a contact member on said means.

7. A thermal relay comprising a bimetallic strip having slits extending such distances, alternately from the respective ends thereof, as to increase the electrical resistance of the strip and means for securing the separated portions of each end of the strip together.

8. A thermal relay comprising a bimetallic strip having slits therein extending from opposite ends thereof and insulating means adjacent the ends thereof for securing the separated portions of the strip together to cause the torques of the several portions to be cumulatively effective.

9. A thermal relay comprising a bimetallic strip having slits therein extending from one end thereof, an insulating clamp for one end of the strip to cause the several portions to move together, means for supporting one end of the strip, and a contact member supported on and controlled by the free end of the strip.

10. A thermal relay comprising a cylindrical casing, two end ferrules therefor, and a thermal-responsive device supported as a unit within the casing on one ferrule and electrically connected between both ferrules.

11. A thermal relay comprising a cylindrical casing, two end ferrules therefor, a bi-

metallic element supported on one ferrule only and means for electrically connecting the same to both ferrules.

12. A thermal relay comprising a cylindrical casing, two end ferrules therefor, a bimetallic element supported on one ferrule only and means for electrically connecting the element to the other ferrule.

13. A thermal relay comprising a cylindrical casing, two end ferrules therefor, a bimetallic element supported on one ferrule only and so slit from the opposite ends thereof as to constitute a conductor of relatively high resistance, means for connecting one end of the conductor thus constituted to the

supporting ferrule and the other end to the other ferrule.

14. A thermal relay comprising a cylindrical casing, two end ferrules therefor, an insulating member, a bimetallic member secured to the insulating member, a stationary contact member mounted on the insulating member, a movable contact member mounted on the bimetallic member and means for mounting the insulating member on one ferrule only. 20 25

In testimony whereof, I have hereunto subscribed my name this 4th day of June, 1920.

HORACE F. BANAN.
